UNITED STATES PATENT OFFICE.

WILLIAM SPARKS, OF JACKSON, MICHIGAN.

DESIGN FOR A MEGAPHONE.

41,825.

Specification for Design.

Patented Oct. 3, 1911.

Application filed March 14, 1911. Serial No. 614,493. Term of patent 14 years.

To all whom it may concern:

Be it known that I, WILLIAM SPARKS, a citizen of the United States, residing at Jackson, in the county of Jackson and State of Michigan, have invented a new, original, and ornamental Design for Megaphones, of which the following is a specification, reference being had to the accompanying drawing, forming part thereof.

Figures 1 and 2 are respectively a side elevation and rear end view of a megaphone showing my new design which consists in the circular base —1— and flaring bell-shaped body —2— terminating in an oval

mouth —3— with an annular bead —4— at the junction of the base —1— with the body —2— and a compound curved branch —5— leading from one side of the main body —2— across the bead —4— and to the rear end of the base —1—.

I claim:

The ornamental design for a megaphone, as shown and described.

WILLIAM SPARKS.
